UNITED STATES PATENT OFFICE.

HARRY S. VINCENT, OF RIDGEWOOD, NEW JERSEY, ASSIGNOR TO FRANKLIN RAILWAY SUPPLY COMPANY, A CORPORATION OF DELAWARE.

DRAFT APPLIANCE FOR BOOSTER-SUPPLEMENTED LOCOMOTIVES.

Application filed February 13, 1928. Serial No. 87,995.

This invention has relation to locomotives which are equipped with so-called booster motors. Such motors are intended to aid the locomotive only in starting or at slow speeds on heavy pulls so that under normal running conditions said motors are normally inoperative or idle.

Steam is supplied to the booster motor from the same source as for the locomotive cylinders, namely, the boiler of the engine. It will therefore be seen that when the booster is in operation the locomotive will have to be supplying steam in greater quantity than when it is not. In booster supplemented locomotives it has been the experience that occasionally the draft of the locomotive is not sufficient to maintain proper steaming when the booster is in operation.

With the foregoing in mind, therefore, the main object of my invention can be stated as involving the provision of an adequate steam supply whenever the boiler is called upon to deliver steam to both the booster motor and the main engine cylinders. More specifically considered I provide means for increasing the draft on the locomotive fire whenever the booster is in operation and to this end I make use of a variable or adjustable nozzle together with a motor device for decreasing the nozzle opening whenever steam is being supplied to the booster motor.

How the foregoing objects are obtained I have illustrated in preferred form in the accompanying drawings, in which

Fig. 1 is a diagrammatic side elevation of a locomotive equipped with a booster and illustrating my invention applied thereto;

Fig. 2 is a vertical mid-section through the locomotive exhaust nozzle showing the manner in which I accomplish the necessary adjustments;

Fig. 3 is an elevation of Fig. 2 taken from the left-hand side; and

Fig. 4 is a section on the line 4—4 of Fig. 2.

In the drawings the locomotive A is of usual construction having the main driving wheels 1, boiler 2, fire box 3, steam dome 4, cylinders 5 and stack 6. Steam is admitted to the cylinders 5 for the purpose of driving the wheels 1 but the details of this are not illustrated as they are common practice and form no part of the present invention.

The booster motor B for aiding the loco-

motive is designed to drive the wheels 7 beneath the fire box 3 and is preferably of the air controlled type now well known in the art and illustrated in detail, for example, in Ingersoll Patent No. 1,339,395 and Peters 60 Patent No. 1,470,761. Steam for operating the booster is delivered thru the pipe 8 and exhausted thru the pipe 9, which, of course, can be extended to any desired point. For instance the exhaust steam from the booster 65 might be carried forward to discharge up the stack or it might be utilized in a feed water heater or other supplemental device on the locomotive or it might exhaust directly to the atmosphere at any one of a 70 number of places.

The exhaust from the cylinders 5 takes place thru the variable or adjustable nozzle C which comprises a main or body casting 10 having the inlet 11 for the exhaust steam, 75 the outlet 12 which defines the maximum area of the exhaust nozzle and the protruding cylindrical portion 13 for housing certain portions of my improved apparatus to be described later. The outlet or nozzle tip 80 12 has an annular interior rib 14 and four vertically disposed spaced ribs 15. Within the nozzle 12 is a member 16 which can be raised and lowered to adjust the effective discharge area of the exhaust nozzle. 85

The member 16 comprises a circular body portion 17 which tapers inwardly as it approaches the point of exhaust. The upper outer edge of the member 17 constitutes a projecting annular rib 18 running downwardly from which are the four vertically disposed ribs 19. There is a central spider 20 by means of which this adjustable member is secured to the stem 21 connected to the operating rod 22 and bell crank lever 23. 90

It will therefore be seen that when the member 16 is in its upper or normal position the exhaust steam can flow out not only thru the central opening 24 but also thru the surrounding annular space 25 but when the adjustable member 16 is in its lower position its annular rib 18 will abut against the annular rib 14 on the interior of the nozzle tip 12 so as to close off the annular passage 25. Under this latter condition all of the exhaust steam must pass thru the interior opening 24. 100

The rod 22 is suitably pivoted at 26 to the stem 21 and at 27 to the bell crank 23, the bell crank itself being pivoted upon the pin 28. 110

The opposite end of the bell crank is pivotally connected to the piston 29 in the cylinder 13 by means of the coupling link 30 suitably pivoted to the two members at 31 and 32.

Steam or other fluid pressure is admitted to the piston 29 thru the cylinder head 33 by means of the pipe or conduit 34 and the piston is arranged to work against the pressure of the spring 35 which latter normally holds the piston 29 in its left-hand position and maintains the member 16 in its upward position where the full exhaust area is made available. If steam is to be used the pipe 34 can be connected to the pipe 8 but if air should be preferred the connection could be made to any suitable point in the air controlling system illustrated in the above mentioned patents, the feature of importance, in each instance, being that the connection be so made that motive fluid be supplied to the piston 29 whenever the booster motor is being operated. In the arrangement illustrated steam is supplied to the piston 29 whenever it is being supplied to the booster motor.

The operation, therefore, is as follows: When the engineer desires to use the booster he admits steam to the pipe or conduit 8 from the dome 4, or from some other source as preferred, which at the same time supplies motive fluid to the motor device D so that the movable member 16 is drawn downwardly to close off the passage 25. While the booster is in operation it will then be necessary for all of the exhaust steam to pass through the interior opening 24 of smaller area which will increase its rate of flow and therefore augment the effective draft created by the exhaust steam jet. As the draft increases the fire will burn more vigorously in the fire box 3 and cause the locomotive to steam to a greater extent than it otherwise would. In this way I am always able to ensure a sufficient quantity of steam for operating the locomotive as well as the booster.

When the booster is to be cut out the engineer closes off the supply of steam to the pipe 8 and consequently the operating fluid for the motor device D is also shut off so that the spring 35 will return the member 16 to its upper position thereby adding the annular space 25 to the area of the exhaust space 24. This will decrease the effective draft of the locomotive and have a tendency to decrease the steaming power since it is not necessary to supply as much steam when the booster is cut out.

I claim:—

1. A locomotive having in combination, a booster motor, an exhaust nozzle, and means for decreasing the size of said nozzle when the booster motor is in operation.

2. A locomotive having in combination, a booster motor, an adjustable exhaust nozzle, a fluid motor device for decreasing the size of the nozzle, and means for supplying said motor device with operating fluid when the booster motor is in operation.

3. A locomotive having in combination, an adjustable exhaust nozzle, a motor device for decreasing the nozzle opening, a booster motor, and means for operating said motor device and said booster motor substantially coincidentally.

4. A steam locomotive having in combination, an adjustable exhaust nozzle, a motor device for decreasing the nozzle opening, a booster motor, means for supplying the booster with steam, and means connecting said motor device with said steam supply means for the booster whereby to effect a decrease in the nozzle opening when the booster is in operation.

5. A steam locomotive having in combination, a variable exhaust nozzle, a normally idle booster motor, and means for decreasing the said variable exhaust opening when the booster is operating.

In testimony whereof, I have hereunto signed my name.

HARRY S. VINCENT.
